UNITED STATES PATENT OFFICE.

ROBERT SHAND, OF LYNN, MASSACHUSETTS, ASSIGNOR TO THE GENERAL ELECTRIC COMPANY, OF NEW YORK.

DESIGN FOR A CASE FOR ELECTRICAL INSTRUMENTS.

SPECIFICATION forming part of Design No. 25,549, dated May 26, 1896.

Application filed February 21, 1896. Serial No. 580,265. Term of patent 14 years.

To all whom it may concern:

Be it known that I, ROBERT SHAND, a citizen of the United States, residing at Lynn, in the county of Essex, State of Massachusetts, have invented and produced a new and original Design for Cases for Electrical Measuring Instruments, of which the following is a specification.

My design is illustrated in the accompanying drawings, in which—

Figure 1 is a perspective view, and Fig. 2 is a section upon the line 2 2 of Fig. 1 of a case constructed according to the design of my invention.

It consists of two parts symmetrical about the center line of the case, and its leading feature is the spheroidal raised portion on the top of the case.

In the drawings, A is the instrument-case, flat upon its upper surface and provided with a spheroidal raised portion C. Its two parts are arranged symmetrically about the center

line. The case is formed with curved sides D D of suitable depth, as shown. The part of its outline indicated at G is formed upon a radius from the center of the bulge or spheroidal raised portion C. The part E is also formed upon this center, so that the entire outline is approximately a circular sector having an interior angle rounded off, as at E. In the upper face A is located a curved opening B. At one end of the case, on the inside thereof, the top is formed with a curved bead F.

Having thus described my invention, what I claim is—

The design for the case of a measuring instrument, substantially as shown and described.

In witness whereof I have hereunto set my hand this 18th day of February, 1896.

ROBERT SHAND.
